Primary Examiner — Mary Ann Calabrese*Assistant Examiner* — Catherine Ho(57) **CLAIM**

The ornamental design for a electrical connector, as shown and described.

DESCRIPTION

FIG. 1 is a front perspective view of the electrical connector, employing my new design;

FIG. 2 is a left side view of FIG. 1;

FIG. 3 is a right side view of FIG. 1;

FIG. 4 is a front end view of FIG. 1;

FIG. 5 is a rear end view of FIG. 1;

FIG. 6 is a top view of FIG. 1; and,

FIG. 7 is a bottom view of FIG. 1.

The broken line portion of the figure drawings is included to show portions of the article that form no part of the claimed design.

1 Claim, 4 Drawing Sheets(56)
